UNITED STATES PATENT OFFICE

JESSE G. KING, OF DAYTON, OHIO, ASSIGNOR TO FRIGIDAIRE CORPORATION, OF DAYTON, OHIO, A CORPORATION OF DELAWARE

REFRIGERATING APPARATUS

Application filed February 28, 1929. Serial No. 343,496.

This invention relates to refrigerating apparatus and especially to that species of refrigerating cabinet known as an ice cream cabinet.

5 An object of the invention is to economically construct an efficient type of refrigerating apparatus commonly referred to as an ice cream cabinet.

Another object of the invention is to make 10 the cooling unit readily removable from the refrigerator cabinet.

Another object of the invention is to sufficiently support the boiler of the cooling unit.

Another object of the invention is to sufficiently protect the food compartments.

Further objects and advantages of the present invention will be apparent from the following description, reference being had to the accompanying drawings, wherein a 20 preferred form of the invention is clearly shown.

In the drawings:

Fig. 1 is a perspective view of an ice cream cabinet constructed according to the invention.

Fig. 2 is a cross section of the cabinet taken on the line 2—2 of Fig. 3.

Fig. 3 is a cross section longitudinally through the cabinet.

30 Fig. 4 is a perspective view of the metal frame work of the cabinet.

Fig. 5 is a partial view of Fig. 2 disclosing the cooling unit being removed from the cabinet.

35 Fig. 6 is a cross section on line 6—6 of Fig. 5.

In Fig. 1 is disclosed a cabinet 10 generally known as an ice cream cabinet having the removable covers 12 on the top thereof. 40 The particular type of cabinet disclosed in this figure is commonly referred to as a two hole portable. On the front side of this cabinet is the removable small panel or cover 11 to which reference will be made more particularly hereinafter.

In Fig. 4 is disclosed the skeleton of the metal frame work 13 of the cabinet. Various parts of this frame work appear in the other cross sectional views of the cabinet.

50 The frame work parts are preferably in the

form of angle irons altho other forms may be adopted. As disclosed in this figure the frame work has the top angle irons 14 and 15 and the bottom angle irons 16 and 17 connected together at the top by the end irons 18 and 19 and at the bottom by the end irons 20 and 21. The top and bottom are connected at the front by the side pieces 22 and 23 and at the back by the side pieces 24 and 25. A smaller compartment at one end is divided off by the angle irons 26, 27, 28 and 29. This compartment is for the location of the motor, compressor, condenser and receiver.

In Fig. 3 this compartment is at the right end but in Fig. 8 it has been located at the left end. The location of the smaller compartment at either end is a matter of choice generally governed by the surrounding structure of the place where the cabinet is to be installed. The L-shaped supports 31 are located in this smaller compartment below the metal portion thereof for the support of the apparatus therein as will be more particularly described later. Corner plates 30 are preferably placed at the various junctures of the frame work to give added strength. A wooden base 32 is preferably placed on the bottom of the larger compartment formed by the frame work 16, 17, 20 and 28. Above this is preferably located a supporting plate 33 for the insulation slabs 34 preferably of cork, for instance, in the form of cork board. Above the insulation 34 is a large tank 35 open at the top and preferably of copper. Insulation slabs, preferably of cork board, 36, 37, 38 and 39 substantially cover the front, rear and sides of the tank 35. A bituminous cement such as hydrolene is poured or brushed or otherwise thoroughly put on the tank and its insulation so that the cement is located between the tank itself and the insulation and is also in all cracks and junctures of the insulation and also thoroughly covers the outside of the insulation. A wood frame work 40 having suitable openings is placed across the top of the frame work and has a groove 103 for the upper flange of the tank 35.

Upon the front side of the cabinet the insulation 36 has an opening therein for the wooden frame work 41 depending from the 100

frame work 40. As disclosed in Fig. 2, on the upper part of one of the sides of the tank 35 is an opening at the frame work 41 and the opening has around it a boiler supporting ring 42 suitably secured to the inside of the tank 35. A boiler or tank sleeve 43 extends thru the opening in the large tank at this point. A small number of tubes or coils 44 depend from the inner end of this boiler as disclosed in Fig. 2.

In Fig. 2 a clamping ring 46 is secured to the outer ring of the boiler 43 in any convenient manner and by means of the removable bolts 97 cooperates with the supporting ring 42 to maintain the boiler in its position extending into the tank 35. Inside the periphery of the boiler is the boiler header 38 located on a supporting ring 47 commonly referred to as a doughnut. Located on the header is the inlet or liquid line valve 49 allowing the entrance of the refrigerant to the boiler as permitted by the needle valve 51 in the bracket 52 which is in turn controlled by the float 50. The liquid refrigerant level 53 and the oil level 54 is disclosed in this Fig. 2. A boiler support 55 is located at a convenient place for the support and location of the free end of the boiler. As disclosed in Fig. 2 this boiler support is preferably a circular sleeve 30 and secured to the side of the tank 35 opposite to the one on which the rim of the boiler is secured. The support 55 has preferably a flange 56 so that it may be conveniently fastened as by soldering to the side of the tank 35. The support 55 is slightly larger in diameter than the boiler so that the end of the boiler fits snugly therein. The support has a cut away portion 57 for the coils 44 as disclosed in Fig. 6 and it has also a guide flange 58 for easy assembly of the boiler into position. A removable insulation 59 preferably Kapok is placed about the boiler header and is preferably covered with removable slabs of insulation 60 such as cork. Over the tank is placed the top 61 and on top of this is the top insulation 62 preferably of cork suitably cemented with a bituminous cement. About this insulation is the frame work members 63, 64, 65 and 66 extending across the top of the cabinet. A wooden top cover 67 extends across the top of the cabinet above the insulation and the wooden frame work and is suitably secured to the same by such means as the screws 104 and is also bolted to the metal frame work by the bolts 76. Food compartments such as the cans 68 and 69 are placed so that they extend downward into the tank 35 and preferably rest on the bottom thereof. These food compartments are preferably made of copper or galvanized steel. These food compartments have a ledge 70 around their periphery for the top plate 61 to rest thereon. Insulating sleeves 71 preferably of rubber composition surround the top of the tank from the plate 61 to the top panel 72

which is preferably of nickel zinc. Rings 73 preferably of stainless steel are lapped over the openings to the food compartments where they join with the top 72. A short sleeve preferably of stainless steel 74 is placed in the top of the food compartments 68 and 69 and a flange 105 is rolled or hammered to close the opening between the sleeve 74 and the compartments 68 and 69 and the sleeve 71. The sleeve 74 has a tight friction fit with the cans 68 and 69. As disclosed in Fig. 3 the compartments 68 and 69 are adapted to receive other cans with closed bottoms that will extend from the bottom of these compartments to the top or to where the sleeve 74 surrounds the interior. A flange 105 is suitably rolled or hammered at the top of open sleeve 74. Brine such as a solution of alcohol or calcium chloride is put into the tank 35 to a suitable height thru the sleeve 102 which is covered ordinarily by the cap 101.

Within the boiler as disclosed in Fig. 2 is the baffle 77 and the suction tube 78, with an oil over-flow hole therein, leading to the suction valve 79. Pipes or conduits lead from the valves 49 and 79 thru openings in the insulation preferably such as disclosed in my pending application S. N. 702,456 to the smaller compartment referred to above. Within this compartment such as disclosed in Fig. 3 is the compressor 80 for withdrawing gaseous refrigerant from the cooling unit, compressing the refrigerant and delivering it to a condenser 81 wherein it is liquefied and from which it is delivered to a receiver 82. The liquid refrigerant is delivered from the receiver to the liquid refrigerant valve 49 of the cooling unit. The compressor is run by the motor 83 thru the motor pulley 84, belt 85 and the combined compressor pulley and fan 86. A suitable valve and snap switch, not disclosed, starts or stops the running of the compressor when the conditions of the system warrant such operation. This refrigerant supply apparatus is preferably supported on the platform 87 and resiliently suspended by the springs 88 from the brackets 31. End panels 89 and 90, a front panel 91 and a rear panel, not disclosed, are placed about the sides of the cabinet and suitably secured thereto to cover and protect the structure within. Louvres 92 and 93 are made in the panels at suitable places so that a cooling draft of air might be more easily set up by the fan 86 in the refrigerant supply compartment.

The cabinet as disclosed in the drawings is sturdy, compact, economical and efficiently constructed. It has the advantage that in case it is necessary for any reason to examine or test the valves 49 or 79 it is only necessary to quickly and easily remove the fastening means for the panel 11 or the panel 96 and easily take out the insulation over the valve. It has heretofore been necessary to remove an entire side of the cabinet to make such an ex-

amination. If it is necessary to remove the boiler 43 for examination or replacement the structure in Figs. 2 and 5 permit such removal with very little withdrawal of the brine and with no dismantling of the cabinet itself. The bolts 97 are quickly and easily removed and the boiler 43 with its depending tubes 44 is tiltably removed from the tank and cabinet as disclosed in Fig. 5. It will be perceived in these figures that the opening in the tank and the opening thru the outer panel of the cabinet are considerably smaller than the extreme contour of the cooling unit with its main boiler 43 and depending tubes 44. The cabinet itself will not be dismantled by such removal. Accordingly cabinets constructed according to the invention can have their cooling unit valves easily and quickly examined and even the cooling unit itself removed without any dismantling of the cabinet. The invention has a further advantage that the weight of the heavy boiler 43 is not borne entirely by one small section of the tank 35 but the weight is distributed by having the end of the boiler likewise supported from another section. This tends to maintain the boiler in the position designed for it and prevents any buckling or cracking of the tank 35 due to the concentration of the support for the boiler at one place. This type of support also permits the tubes 44 to hang specifically in the place designed for them without any danger of wearing contact with any other part of the apparatus. Provision of the stainless steel sleeve 74 affords complete protection to the food from any possible corrosion or contamination. The stainless steel sleeve 74 besides presenting a bright and polished appearance is very easily cleaned. The invention is not restricted to the particular type of cabinet disclosed but various features of the invention are applicable to other types of cabinet.

While the form of embodiment of the invention as herein disclosed constitutes a preferred form, it is to be understood that other forms might be adopted, all coming within the scope of the claims which follow.

What is claimed is as follows.

1. In a refrigerating cabinet, a tank, a cooling unit extending through an opening in a side wall of said tank, said opening being smaller than the extreme contour of said cooling unit, insulation over a portion of said tank, a panel about said insulation, said insulation and panel having openings in line with the opening in the side of the tank, said cooling unit being so proportioned that it may be tiltably removed from said cabinet through said openings.

2. In a refrigerating cabinet, a tank, a cooling unit extending through an opening in a side wall of said tank, cooling surfaces depending from the inner end of said cooling unit, said opening being smaller than

the extreme contour of said cooling unit, insulation about said tank, a panel over a portion of said insulation, said insulation and panel having openings in line with the opening in the side of the tank, said cooling unit being so proportioned that it may be tiltably removed from said cabinet through said openings. 70

3. In a refrigerating cabinet, a tank, a cooling unit extending through an opening 75 in a side wall of said tank, tubes depending from the inner end of said cooling unit, said opening being smaller than the extreme contour of said cooling unit, insulation over a portion of said tank, a panel about said insulation, said insulation and panel having openings in line with the opening in the side of the tank, said cooling unit being so proportioned that it may be tiltably removed from said cabinet through said opening. 80

4. In a refrigerating cabinet, the combination with a tank, of an elongated cooling unit extending through an opening in a side wall of said tank, the longitudinal length 90 of said cooling unit being greater than the size of said opening, said opening being smaller than the extreme extent of the contour of said cooling unit inside said tank, and said cooling unit being so proportioned that it is tiltably removable from said tank 95 through said opening.

5. In a refrigerator cabinet, the combination with a tank, of a cooling unit comprising an elongated container for liquid refrigerant extending through an opening in 100 a side wall of said tank, said container having one or more conduits depending therefrom within said tank for the circulation of refrigerant, the length of said container being greater than the greatest extent of said 105 opening, said opening being smaller than the greatest extent of the cross section of said cooling unit through said conduits, said container with said conduits being so proportioned that it is tiltably removable from 110 said tank through said opening.

6. In a refrigerating cabinet, the combination with a tank, of a cooling unit extending through an opening in a side wall of said tank, said opening being smaller than the extreme extent of the contour of said cooling unit inside said tank, said cooling unit being so proportioned that it is longitudinally removable through said opening to a predetermined position and then tiltably removable from said tank through said opening. 115

7. In a refrigerating cabinet, the combination with a tank, of a cooling unit comprising an elongated container for liquid refrigerant extending through an opening in a side 120 wall of said tank, said container having a conduit depending therefrom within said tank, the length of said container being greater than the size of said opening, said opening being smaller than the greatest extent 125

of the cross section of said cooling unit through said conduit, and said cooling unit being so proportioned that it is longitudinally removable through said opening to a predetermined position and then tiltably removable from said tank through said opening.

8. In a refrigerating cabinet, the combination with a tank, of a cooling unit comprising a container for liquid refrigerant extending through an opening in a side wall of said tank, said container having a plurality of conduits depending therefrom within said tank, said opening being smaller than the greatest extent of the cross section of said cooling unit through said conduits, and said cooling unit being so proportioned that it is longitudinally removable through said opening to a predetermined position and then tiltably removable from said tank through said opening.

9. In a refrigerating cabinet, the combination with a tank, of a cooling unit extending through an opening in a wall of said tank, said opening being smaller than the extreme extent of the contour of said cooling unit inside said tank, said cooling unit being so proportioned that it is removable in one direction through said opening to a predetermined position and then tiltably removable from said tank through said opening.

10. In a refrigerating cabinet, the combination with a tank, of a cooling unit extending through an opening in a wall of said tank, said cooling unit having one or more cooling surfaces attached thereto within said tank, said opening being smaller than the greatest extent of the cross section of said cooling unit through said cooling surfaces, said cooling unit being so proportioned that it is tiltably removable from said tank through said opening.

In testimony whereof I hereto affix my signature.

JESSE G. KING.
